Primary Examiner — Nathan M Johnston(57) **CLAIM**

The ornamental design for a tension pole shower caddy, as shown and described.

DESCRIPTION

FIG. 1 is a front perspective view of a tension pole shower caddy, showing my new design;

FIG. 2 is a front view thereof;

FIG. 3 is a rear view thereof;

FIG. 4 is a left side view thereof;

FIG. 5 is a right side view thereof;

FIG. 6 is an enlarged plan of the top surface; and,

FIG. 7 is an enlarged plan of the bottom surface.

The dashed broken lines depict portions of the tension pole shower caddy that form no part of the claim.

1 Claim, 7 Drawing Sheets(56)
